UNITED STATES PATENT OFFICE.

ALBERT E. HARKNESS, OF BRADFORD, PENNSYLVANIA.

REAMER.

1,146,250.

Specification of Letters Patent. Patented July 13, 1915.

Application filed October 6, 1911. Serial No. 653,218.

To all whom it may concern:

Be it known that I, ALBERT E. HARKNESS, citizen of the United States, residing at Bradford, in the county of McKean and State of Pennsylvania, have invented certain new and useful Improvements in Reamers, of which the following is a specification.

This invention relates to improvements in reamers, more particularly to what are known as under reamers which are employed for enlarging the bore of Artesian or like drilled wells where a casing is used and the tool introduced and withdrawn through the casing, and employed to enlarge the drill hole in advance of the casing, and has for one of its objects to improve the construction and increase the efficiency and utility of devices of this character.

With this and other objects in view, the invention consists in certain novel features of construction as hereinafter shown and described, and then specifically pointed out in the claims, and in the drawings illustrative of the preferred embodiment of the invention: Figure 1 is a side elevation of the improved device partly in section; Fig. 2 is a front elevation of the improved device partly in section; Figs. 3 and 4 are perspective views of the reamer bits detached; Fig. 5 is a longitudinal section on the line 5—5 of Fig. 2 with the bits in operative position; Fig. 6 is a perspective view of the stock or body portion of the improved device; Fig. 7 is a view similar to Fig. 4 with the bits in withdrawn position to permit the device to be inserted into the well hole through the casing; Fig. 8 is a plan view of the set ring, detached.

Corresponding and like parts are referred to in the following description and indicated in all the views of the accompanying drawings by the same reference characters.

The stock or body is represented as a whole at 10, and is formed with the usual tapered threaded stud at the upper end to receive the "jar" device or operating rope, and with a transverse opening 11 near its lower end and reduced between the bottom 50 of the opening and the bottom of the stock as represented at 12, and with inclined portions 13 at the juncture of the reduced portion 12 and the bottom of the stock at the sides of the opening. At its upper end the stock 10 is longitudinally bored as represented at 14 and the bore reduced at its inner

end as shown at 15, and communicating by the reduced portion with the interior of the opening 11. The reamer bits are represented respectively at 16 and each includes an upper reduced portion 17 to closely engage in the opening 11 and with inwardly directed upper ends 18, the inwardly directed ends having half sockets in their confronting faces. The reamer bits are provided with lateral offsets 19 with their upper faces inclined and engaging the inclined projections 13 of the stock. The reamer bits are inclined slightly below the shoulders 19 as shown at 20 to correspond with the inclined side faces of the portion 12 of the stock. Below the inclined faces 20 the reamer bits are diverged as shown, and formed with cutting terminals. The reamer bits thus diverge in opposite directions at their lower portions and closely engage against the reduced projection 12 and beneath the inclined overhangs 13 with the inturned terminals 18 engaging by their confronting faces beneath the reduced portions 15 of the bore and registering therewith. A rod 23 extends through the reduced bore 15 of the stock and is provided with a laterally enlarged head 24 at its lower end which bears beneath the overhang portions 18, while the latter engage against the bolt 23 by their half sockets. The bolt 23 extends into the enlarged bore 14 and is connected by a chain 25 to an eye bolt 26 the latter being threaded and provided with a nut 27, and washer 28, the nut and washer being located relatively near the outer end of the stock. A coil spring 29 surrounds the chain 25 and exerts its force to maintain the head 24 yieldably in engagement with the overhang portions 18 of the cutting bits and thus holds them yieldably in position.

The bits 16 are provided with projections 21 and inwardly directed stop shoulders 22, the object to be hereafter explained.

Surrounding the stock 10 opposite the aperture 11 and the reduced upper portions 17 of the bits, is a band or sleeve 30 secured in place by stop pins 31 or other fastening devices, and serving to retain the bits in position and prevent their displacement in event of the breakage of the operating rod. The reduced web 12 of the stock is provided with a longitudinal bore, while the lateral enlargement 24 of the rod 23 is provided with a threaded socket so that an operating rod 32 may be inserted through the bore of

the web 12 and engaged with the head 24 of the rod 23, to enable the rod 23 and its head 24 to be withdrawn against the resistance of the spring 29 to enable the bits 5 to be drawn outwardly and the shoulders 22 engaged with the reduced portion 12 as shown in Fig. 5, to enable the device to be inserted into the casing represented at 33. A split setting ring 34 is placed tempor- 10 rarely around the bits as shown in Fig. 7, and the rod 32 detached, the ring operating to hold the bits in withdrawn position until the cutting ends of the bits have been inserted into the casing. After this the pro- 15 jections 21 by engaging against the interior of the casing will hold the bits in closed position and permit the device to be lowered into the well.

As soon as the improved device reaches 20 the bottom of the well and the projections 21 pass below the lower end of the casing, the reaction of the spring 29 will release the shoulders 22 from the projection 12 and re- 25 store the bits to their operative and distend- ed position as shown in Fig. 1. Thereafter the device may be employed as a reamer to enlarge the opening beneath the casing by motion imparted to the operating rod in the ordinary manner. When it is desired to re- 30 move the device from the well, it is only necessary to draw it forcibly upward until the projections 21 again engage against the casing 33 when the latter will operate to lower the bits against the resistance of the 35 spring 29, and again connect the shoulders 22 with the projection 12, this movement as will be obvious, withdrawing the cutting ends of the bits and disposing them in the position shown in Fig. 7, enabling the de- 40 vice to be withdrawn. As soon as the bits have been moved to a sufficient extent above the upper end of the casing the split hold- 45 ing ring 34 can be again placed around the bits and thus hold them in closed position.

The stock 10 is formed relatively heavy to 50 enable it to withstand the severe strains and shocks to which it will be subjected when in use, while the cutting bits are likewise relatively heavy and solid for the same purpose.

The overhang portions 18 of the bits are provided with upwardly directed projec- 55 tions 35 which engage in corresponding recesses in the stock 10, as shown in Fig. 5, and thus relieve the sleeve 30 from a portion of the strain.

Having thus described the invention, what is claimed as new is:

1. In a device of the character described, 60 a stock, a substantially wedge-shaped projection formed on the lower end of the stock, pairs of spaced undercut shoulders formed on the stock at diametrically opposite portions thereof, said shoulders having their lower faces extending at an acute angle

to the active faces of the projection, a pair of cutting blades, each of said cutting blades being provided on each side with a beveled lateral shoulder, said shoulders being adapted to engage against the 70 shoulders of the stock, each cutting blade having intermediate portions of its inner face beveled whereby the intermediate portions of the blades will engage flatly against the active faces of the projection when the 75 shoulders of the blades are in locking engagement with the shoulder of the stock, and yieldable means arranged in the stock for normally holding the blades in operative position. 80

2. In a device of the character described, a stock having a transverse opening, cutting bits having their upper portions engaging in the opening of the stock and a removable sleeve incasing the stock for holding the bits against accidental displacement, said sleeve being movable upwardly to release the bits. 85

3. In a device of the character described, a stock having a transverse opening, a pair 90 of co-acting cutting bits having inwardly directed extensions formed on their upper terminals, said extensions being received within the transverse opening of the stock, yieldable means normally holding the ex- 95 tensions at the upper terminal of the transverse opening and a sleeve removably mounted on the stock and partially closing the transverse opening thereof, the unclosed portion of the transverse opening being of 100 less width than the said extensions whereby the bits are normally held against accidental withdrawal from the stock, and yieldable means carried by the stock and en- 105 gageable with the extensions of the bits for normally holding the bits in operative position.

4. In a device of the character described, a stock, cutting blades removably engaging the stock, co-acting shoulders formed on the 110 stock and cutting blades for rigidly holding the blades in operative position, yieldable means for normally holding the shoulders of the blades in engagement with the shoulders of the stock, and a sleeve removably 115 mounted on the stock for normally holding the blades against removal therefrom, said sleeve being movable upwardly to release the blades. 120

5. In a tool of the character specified, a 120 stock having a transverse opening near its lower end and a central longitudinally ex- 125 tends wedge-shaped projection below the opening with its lower end oppositely inclined and having under cut shoulders at opposite sides of the transverse opening and wedge-shaped projection, cutting blades ar- 130 ranged upon opposite sides of the wedge-shaped projection and having inwardly di- 135 rected projections at their upper ends to ex- 140

tend over the said projection and operate in the transverse opening, and having inwardly extending intermediate portions to ride upon the faces of the said wedge-projection, and having intermediate lateral shoulders which are outwardly and downwardly inclined to engage under the undercut shoulders of the said wedge projection, means for retaining the cutting blades in place, and yieldable connecting means be-

tween the cutting blades and stock normally exerting an upward pull upon the cutting blades.

In testimony whereof I affix my signature in presence of two witnesses.
